UNITED STATES PATENT OFFICE

2,421,993

SHOE FOR PILES

Walter H. Cobi, New York, N. Y., assignor of one-half to John J. Dougherty, St. Albans, N. Y.

Application October 3, 1945, Serial No. 620,105

6 Claims. (Cl. 61—78)

1

My invention relates to tips or shoes for foundation piles and especially for those having tubular shells which are driven and filled with concrete or cement.

The main object is to provide a shoe or tip capable of at the same time reenforcing the lower end of a tube and concentrating the soil at and adjacent thereto.

Another object is to provide a tip or shoe of maximum strength and a minimum weight.

Another object is to provide a shoe or tip which can be readily manufactured.

I have accordingly provided a shoe which can be of cast, pressed or forged metal and fitted to the lower end of a tube. This shoe preferably has a shoulder to take the thrust of the tube and a cutting edge substantially in line with the end of the tube and a central recess with walls of substantially uniform thickness extending upwardly from the cutting edge so that when the tube or pile is driven the earth beneath the shoe is compressed. A full bearing for the pile is thus provided.

Details of the improvement are illustrated and will be described.

Fig. 1 is a vertical cross sectional view of a tube or pile shoe embodying my invention.

Fig. 2 is a sectional view showing a shoe fitted to a pile tip and just started to be driven into the ground.

Fig. 3 is a similar view showing the end of the pile with the shoe driven further into the soil.

Figs. 4 and 5 are fragmentary vertical sectional views showing modifications.

Fig. 6 is a horizontal sectional view of one-half of a corrugated tube.

The shoe is preferably formed in one piece like an inverted cup and has a shoulder 1 to take the thrust of the tube 8. Beneath this shoulder 1 is a cutting edge 9. An inclined wall 10 serves to center the tube as the shoe is applied. An outer flange 11 is also preferably provided to reinforce the tube and add to the bearing area. Between the wall 10 and flange 11 is a groove 12 into which the end of the tube is fitted. From the cutting edge 9, the walls 13 of the shoe arch upwardly preferably on a parabolic curve to form a pocket or recess 14 so as to draw inwardly and compress the soil within this recess when the tube or pile is driven.

2

This construction affords an easy start for the driving operation and a maximum support for the driven pile.

The shoe also reinforces and protects the lower end of the pile and prevents it from bending or splitting.

To add to the rigidity and to ensure closure at the end of the tube, the flange 11 may be welded to the tube as indicated at 8'.

10 The tube may be seamless or welded and of any suitable cross-section, for instance, cylindrical as shown in Fig. 2 or corrugated as shown in Fig. 6 or fluted. The shoe of course will be shaped to fit the tube. So also the lower end of the shoe 15 may have a continuous cutting edge as shown in Figs. 1 to 3 or the edge may be serrated or toothed as shown at 15 in Fig. 4.

The arched central portion of the tip not only assists in centering the tip on the tube but affords 20 a maximum strength for a minimum weight of metal.

I claim:

1. A metal shoe for a pile tube comprising a central arched portion having a recess below and 25 having an exterior annular shoulder formed above and around the rim for receiving the annular end of the tube and having a lower cutting edge surrounding said recess for drawing in and compressing soil within said recess.

30 2. A pile shoe comprising a rigid imperforate metallic body fitted to support a pile tube and having an arched central portion with a recess of parabolic section in its lower face, the lower wall of which terminates in a cutting edge.

35 3. A pile shoe comprising a rigid body having a peripheral flange with a seat around its upper face for supporting a pile tube and having an arched central portion with a recess in its lower face terminating in a cutting edge in approximate 40 alignment with the tube seat.

4. A metallic pile shoe having an arched central wall of substantially uniform thickness and with a recess therebelow, a cutting edge surrounding its lower edge, a tube seat above said edge and a flange surrounding said seat.

45 5. A metallic pile shoe having a peripheral cutting edge surrounding a recess having inwardly and upwardly arched walls adapted to center a 50 pile tube and concentrate the soil beneath it to-

ward the center as the pile tube is driven, said shoe having a shoulder on which the pile tube rests.

6. The combination of a tubular metallic pile and a metallic shoe mounted on the end thereof, said shoe comprising a central arched portion having a recess below and having an exterior annular shoulder formed above and around the rim of its recess for receiving the annular end of the tube and having a lower cutting edge surrounding said recess for drawing in and compressing soil within said recess, the end of the tube being welded to said shoe.
